UNITED STATES PATENT OFFICE.

JOSEPH T. THOMPSON, OF VERONA, NEW YORK.

ICE-SCRAPER.

SPECIFICATION forming part of Letters Patent No. 340,169, dated April 20, 1886.

Application filed February 8, 1886. Serial No. 191,121. (No model.)

To all whom it may concern:

Be it known that I, JOSEPH T. THOMPSON, of Verona, in the county of Oneida, in the State of New York, have invented new and 5 useful Improvements in Ice-Scrapers, of which the following, taken in connection with the accompanying drawings, is a full, clear, and exact description.

The purpose of this invention is to expeditiously and effectually clean fields of ice from superincumbent snow preparatory to harvesting said ice or using it for skating thereon; and the invention consists in a novel organization of the constituent members of an ice-scaper, as hereinafter fully described, and specifically set forth.

In the annexed drawings, Figure I is an isometric view of my improved ice-scaper. Fig. II is a vertical longitudinal section of the 20 same. Fig. III is a detail view of the scraping-plate and the means for holding it in its operative position, and for releasing it to allow it to dump; and Fig. IV is a detached plan view of the crank-shaft by means of 25 which the scraping-plate is raised, so as to allow it to dump.

R R are two longitudinal side plates, having the bottom corner at the front rounded off to make said plates serve as runners, said runners being united by cross-bars A A', which are firmly attached to the upper part thereof, and form therewith a rigid frame. The rear portions of the two side plates or runners R R are provided with slots c c, and through said 35 slots project the ends of a shaft, a, which is extended across the frame.

Transversely between the two runners R R is the scraping-plate C, pivoted on the shaft a. Said plate, when in its operative position, 40 rests with the back of its upper portion against the cross-bar A', and is inclined forward, and has its bottom edge even with the bottom of the runners, as represented in Fig. 1 of the drawings. The scraping-plate is provided with 45 forward-projecting side flanges, v v, by which it abuts against the inner sides of the runners R R. A rectangular scoop is thus formed in front of the scraping-plate.

On the outer sides of the runners, and forward from the slots c c, are pivoted the levers L L, and to these levers are attached the ends

of the shaft a, on which the scraping-plate is hinged. I do not, however, limit myself specifically to the aforesaid pivoting of the scraping-plate on the shaft a, as it is obvious that 55 trunnions may be rigidly attached to the scraping-plate and pivoted on the levers L L. The essential feature in this respect is the pivoting of the scraping-plate C transversely between the runners and carrying said plate on the levers L L, as will become apparent hereinafter.

Back of the cross-bar A' is another shaft, e, extended across the frame and through the runners R R, at the outer side of which said 60 shaft is formed with cranked arms e e, terminating in trunnions, which project outward and through slotted plates f f, attached to the free ends of the levers L L.

By means of a lever, D, attached to the 70 shaft e, the latter can be turned so as to cause the cranked arms e e thereof to swing upward and forward, and thereby lift the scraping-plate C into the position indicated by dotted lines in Figs. 1 and 3 of the drawings, and 75 when in this position the lever D lies against the back of the cross-bar A', and the cranked arms e e stand at such a forward inclination and such an angle with the levers L L as to partially lock said parts in their positions and 80 render the scraping-plate C self-sustaining in its elevated position, this position being required while moving the apparatus over the road to and from the ice, and also to allow the scraping-plate to be dumped or inverted, 85 as illustrated in Fig. 2 of the drawings. A lever, d, rigidly attached to and projecting rearward from the top of the scraping-plate, allows said plate to be swung back by the operator standing on the platform P, extended 90 across the rear portion of the frame.

To the inner sides of the runners R R are attached lugs or stop-pins t, which arrest the tilting of the scraping-plate when dumped.

On the rear cross-bar, A', is pivoted a two- 95 armed latch, b, one arm of which reaches over the top and partly over the front of the scraping-plate C when in its operative position, and the other arm of the latch projects downward at the rear of the cross-bar A', and has its 100 free end between two shoulders of a cam, h, attached to the shaft e. In turning the shaft

so as to cause the levers L L to lift the scraping-plate C, as hereinbefore described, the upper shoulder of the cam h presses the downward-projecting arm of the latch b forward, and thereby throws the other arm of said latch upward, so as to release the scraping-plate C simultaneously with the lifting of the same. Said plate then automatically tilts into its dumped or inverted position. The partial locking of the shaft e in its position by the forwardly-inclined lever D and cranked arms e' e' of said shaft, as hereinbefore described, causes the cam h to retain the latch in its raised position, as illustrated in Fig. 2 of the drawings, until the upper part of the scraping-plate C is thrown back against the cross-bar A' and the shaft e turned to cause the cranked arms e' e' thereof to allow the levers L L to descend and lower the scraping-plate to its operative position. During this latter movement of the shaft e the cam h swings the latch b into position to engage the top of the scraping-plate and retain it in its operative position.

To the front end of each runner R, I connect a vertically-adjustable scraper, i, which, with the scraper i of the other runner, stands convergently toward the space between the runners, so as to convey in that direction the snow gathered in front of the said scrapers. These scrapers have vertical shanks j, which pass loosely through clips r r on the runners R R, and project above the latter, and are perforated at their upper ends. Across the top of the frame is extended a shaft, l, which is journaled in eyebolts u u, or other suitable bearings secured to the top of the runners. From the ends of the shaft l project forward two arms, m m, the ends of which pass through the perforations of the upper ends of the scrapers j. From the shaft l projects vertically a lever-arm, n, and to the upper end of the latter is connected a rearwardly-extended rod, o, which terminates with a suitable handle and in a convenient position for manipulation by the operator, standing on the platform p. By drawing the rod o rearward the scrapers i i are raised while drawing the apparatus over the road to and from the ice-field, and in the operation of scraping the ice the rod o is pushed forward to lower the scrapers i i, so as to scrape the snow from the ice in front of the runners and allow said runners and main scraping-plate C to run directly on the surface of the ice, and thus effectually scrape the snow from the ice. The side plates or solid runners, R R, gather the snow between them in front of the scraping-plate C, and when the space inclosed by said parts is filled the gathered snow can be conveyed to a distant place of deposit without further scraping the ice and gathering the snow by raising the scrapers i i in front of the runners, so as to allow the latter to run on top of the snow. Upon arrival at the place of deposit the operator raises the lever D and throws it forward against the rear cross-bar, A', and thereby causes the shaft e, with its cam h and cranked arms e' e', to

throw the latch b out of engagement with the scraping-plate C, and simultaneously raise the levers L L, so as to lift the scraping-plate, 70 which latter then automatically turns on its axis and dumps, as represented in Fig. 2 of the drawings. After the apparatus is conveyed back into position for scraping the ice, the operator lowers the scrapers i i by pushing the rod o forward, and swings the top of the main scraping-plate C back by the lever d, and lowers said plate by swinging the lever D rearward and downward into the position shown in Figs. 1 and 2 of the drawings. The 80 apparatus is then again in condition for thoroughly and cleanly scraping the snow from the ice and gathering said snow.

Having described my invention, what I claim as new, and desire to secure by Letters Patent, 85 is—

1. In an ice scraper, the combination of two runners, a scraping-plate pivoted transversely between the runners and on a vertically-movable axis, a latch adapted to retain the scraping-plate in its operative position and to release it for dumping, and a lever for raising and lowering the axis of the scraping-plate, 90 substantially as and for the purpose set forth.

2. In an ice-scraper, the combination of two runners, a scraping-plate pivoted transversely between the runners and on a vertically-movable axis, a latch adapted to engage and release said scraping-plate, a lever for raising and lowering the axis of said plate, and a lever 95 for dumping the scraping-plate, substantially 100 as set forth.

3. The combination of the runners R R, the levers L L, pivoted on said runners, the shaft a, attached to said levers, the scraping-plate 105 C, pivoted on said shaft, and the latch b, adapted to retain the plate C in its operative position, substantially as described and shown.

4. The combination of the runners R R, provided with the slots c c, the levers L L, pivoted to the outer sides of the runners, the shaft a, extended through said slots and connected to the levers, the scraping-plate C, pivoted on said shaft, the latch b, adapted to retain the plate C in its operative position, and the lever 110 d, for dumping the scraping-plate, substantially 115 as described and shown.

5. The combination of the runners R R, provided with slots c c, the levers L L, pivoted on the outer sides of the runners, the shaft a, extended through said slots and connected to the levers, the scraping-plate C, pivoted on said shaft, the shaft e, having cranked arms e' connected with the free ends of the levers L L, and the lever D, attached to the shaft e, for turning 120 the same, substantially as set forth and shown.

6. The combination of the runners R R, provided with slots c c and united by cross-bars A A', the levers L L, pivoted on the outer sides of the runners, the shaft a, extended through 130 said slots and connected to said levers, the scraping-plate C, pivoted on said shaft, the slotted plates f f, attached to the levers L L, the shaft e, having cranked arms e' e', entering the slotted

plates *ff*, the lever *D*, and cam *h*, attached to the shaft *e*, the latch *b*, pivoted on the cross-bar *A'*, and actuated by the aforesaid cam, and the lever *d*, attached to the scraper-plate, substantially as described and shown.

7. In combination with the runners *R R* and the scraping-plate *C* between said runners, the scrapers *i i*, connected vertically adjustable on the front end of the runners, substantially as and for the purpose set forth.

8. In combination with the runners *R R* and the scraping-plate *C* between said runners, the scrapers *i i*, connected vertically adjustable on the front end of the runners and standing convergent toward the space between the runners, substantially as and for the purpose set forth.

9. In combination with the runners *R R* and

the scraping-plate *C* between the runners, the scrapers *i i*, connected vertically adjustable on the front end of the runners, the shaft *l*, pivoted on top of the runners and having arms *m m*, connected with the scrapers *i i*, the lever-arm *n*, projecting vertically from the shaft *l*, and the rod *o*, extended rearward from the said arm, substantially as described and shown.

In testimony whereof I have hereunto signed my name and affixed my seal, in the presence of two attesting witnesses, at Syracuse, in the county of Onondaga, in the State of New York. this 5th day of February, 1886.

JOSEPH T. THOMPSON. [L. S.]
